CLAIM

The ornamental design for a cover for a crutch, as shown and described.

DESCRIPTION

FIG. 1 is a perspective view of a crutch cover comprising a lower crutch cover, a hand grip cover, an arm rest cover and an accessory pouch showing my new design;

FIG. 2 is a front elevation view thereof;

FIG. 3 is a right side elevation view thereof;

FIG. 4 is a plan (top) view thereof;

FIG. 5 is a rear elevation view thereof;

FIG. 6 is a left side elevation view thereof;

FIG. 7 is a bottom view thereof;

FIG. 8 is a section view showing the arrangement of the arm rest cover;

FIG. 9 is a section view showing the hand grip cover; and,

FIG. 10 is a section view showing the lower crutch cover and the accessory pouch.

The broken line showing of a crutch in FIGS. 1-5 and 7-9 is for illustrative purposes only and forms no part of the claimed design.
